EXTENDABLE SIGN EXHIBITOR

George E. Sweetnam, Chicago, Ill.

Application October 23, 1951, Serial No. 252,785

4 Claims. (Cl. 40—139)

The following specification relates to an improved extendable sign exhibitor of value in advertising where it is desired to modify the optical impression by variation in size or position of the indicia.

The eye is attracted and the attention of the observer increased by a change in the appearance of a sign whether by movement of the sign or in a change in the proportions of the component lettering.

In order to give the desired effect it is necessary to modify the sign in only one dimension. This invention is directed to improved means for accomplishing a result of this character.

One object of the invention is to give the sign exhibitor an illusion of action. The impression desired indicates the idea of motion, specifically, such motion as can be associated with the thought of growth, increase, or enlargement.

One object of this invention is to produce an elongation of the sign in one direction by extending one or more moveable portions of the sign by mechanical means capable of repeating the change in appearance at periodic intervals.

A further object of the invention is to provide a sign having a fixed portion and a second portion or panel moved relatively to the fixed portion by mechanical means, which latter in itself is a novel feature.

A further object of the invention is to provide a sign having panels which slide in opposite directions simultaneously in timed frequency.

A still further object of the invention is to provide a motor driven, movable element for imparting movement to two panel elements simultaneously in opposite directions.

For the purpose of illustrating the invention I have illustrated the preferred form on the accompanying drawings in which

Fig. 1 is a front elevation of the novel sign exhibitor in contracted position;

Fig. 2 is a similar view of the sign having portions extended vertically;

Fig. 3 is a rear elevation of the sign on an enlarged scale and in extended position;

Fig. 4 is an enlarged plan view of the exhibitor partly in section;

Fig. 5 is a vertical section on the line 5—5 of Fig. 4;

Fig. 6 is a side elevation of the motor and eccentric drive taken on the line 6—6 of Fig. 5;

Fig. 7 is a rear elevation of a modified form;

Fig. 8 is a vertical section on the line 8—8 of Fig. 7;

Fig. 9 is a rear elevation of a further modification; and

Fig. 10 is a vertical section on the line 10—10 of Fig. 9.

Briefly described, the invention consists in a device which is actuated by a motor and given a motion for creating an illusion of action, elongation or the like, to printed, painted or hand lettered words, objects, scenes or human figures. This result is accomplished by the use of light weight panels made of suitable paper, card-

2

board, metal, wood or plastic sheets. These panels are set in a frame work, with one panel remaining in a fixed position. One or more panels are set in motion by mechanical means. This motion shows what appears to be a stationary object, letter or the like, to be elongated or stretched to a different size, shape or degree of visibility. It is also apparent that suitable control having elongation or stretching motion can be given to one or more letters of a word, while the remaining letters are unchanged. Also, the motion can be so controlled that one word of the sentence or slogan can be given the changed appearance by motion, while the remaining words are motionless.

The principle is that of elongating or stretching a part only of the reproduction of objects, scenes, or human figures, so that one or more objects can be brought into view, or the size or shape of one or more objects can be visibly changed while the remainder of the picture is unchanged.

The invention is of particular advantage when applied to advertising material such as window displays, counter cards, signs and outdoor billboards, printed bulletins and spectaculairs.

As illustrating the preferred form or embodiment of my invention I have shown it to consist in a housing 1, of metal, wood, fibreboard or the like. This housing has a front opening 2, through which the sign is displayed.

A frame 3 is suitably supported within the housing. The frame 3 also has a front window in registry with the opening 2 in the housing 1.

The frame 3 has side flanges 5 which are bent to the rear and used for reinforcement of the frame and for the support of the parts within the frame.

Thus the side flanges 5 are slotted as at 6 to receive the side tongue 7 of a fixed panel 8. This panel is spaced from the front surface of the frame 3 to provide for movement of one or more movable panels, as shown in Fig. 5. The fixed panel 8 is cut away at the top and bottom as indicated at 9 and 10. This provides freedom for the movement of the movable panels.

A horizontal and laterally extending track 11 is attached by any suitable means to the rear of the fixed panel 8. This track carries a slide 12 which moves horizontally from one side of the frame 3 to the other. The slide has one or more pivots 13 by which it supports the movable panels.

The upper movable panel 14 slides vertically behind the frame 3, in front of the fixed panel 8 and between the extended portions of the latter which form the opening 9.

To accomplish this result the panel 14 is preferably provided with pivots 15, 15. Two parallel links 16, 16 are mounted on pivots 15, 15 and have their lower ends pivotally connected to a pivot 13 on the slide 12.

Where two such links are provided as shown in Figs. 5 to 5 inclusive, the movable panel 14 is thus held in fixed horizontal position or parallelism, regardless of the vertical movement which it may be given by the travel of the slide 12 from side to side.

A lower movable panel 17 is likewise carried behind the frame 3, in front of the fixed panel 8 and between the portions of the latter forming the cut-out 10. Two pivot pins 18, 18 are provided along the lower edge of the movable panel 17 and are connected by parallel links 19, 19 to the pivot panel 13 on the slide 12.

The lower panel 17 is therefore caused to reciprocate vertically simultaneously with the upper panel 14. This reciprocation, however, is in the opposite direction.

The movements of the two slidable panels relative to the fixed panel 8 makes possible the appearance of the sign as indicated for example in Figs. 1 and 2. Here, the word "Save" appears to be printed partly on the fixed

panel and partly on the two movable panels. The lettering is constricted vertically by the latter panels or brought inwardly of the frame.

However, as shown in Fig. 2, the panels which move vertically in opposite directions, separate to disclose a greater area of the fixed panel 8. As the latter is lettered appropriately to the word, the portions on the movable panels are connected by extended portions of the letters. Thus the optical impression is that of enlargement, increase, or similar effect.

It will readily be appreciated that other verbs of action, such as "Go" and similar insignia may be used to indicate a sign which will attract attention and impart an advertising idea.

In like manner, the change may be imparted to a picture, design or the like, so that the optical impression is varied for the desired purpose.

In Figs. 3 to 6 inclusive, I have shown the use of a rotary electric motor and means for converting its rotary motion into the reciprocating movement of the slide 12.

Two supporting bars 20, 20 have terminal lugs 21, 21 which are seated in appropriate slots in the side flanges 5. These bars form a reinforcement for the frame and at the same time a support for the electric motor. For the latter purpose the bars are connected by a vertical post 22. This post carries an electric motor 23, as shown more clearly in Fig. 5. A flywheel 24 is mounted on the end of the rotary shaft of the motor. This flywheel has a pair of aligned spring clips 25 mounted diametrically on its outer face.

A crank disc 26 is provided with corresponding aligned slots 27, 27. These slots receive the spring clips 25, 25 when the crank disc 26 is removably mounted on the flywheel 24. The crank disk 26 carries a crank pin 28, as shown in Fig. 6.

There is a connecting rod 29 which runs from the crank pin 28 to one end of the slide 12 where it is pivotally carried by a pin 13.

When the small electric motor is running, the movement of the crank 28 and connecting rod 29 causes the slide 12 to reciprocate horizontally. In this manner, the two movable panels 14 and 17 move in opposite directions to produce the changeable impression above described.

Another method of causing the simultaneous reciprocation of the movable panels 14 and 17 is shown in Figs. 7 and 8. Here, the fixed panel 8 is mounted as above described. However, this panel has two vertically aligned slots 31, 31.

These slots permit lugs 32, 33 mounted on the back of each panel 14 and 17 respectively, to project back of the fixed panel.

The bars 20, 20 have a post 34 for supporting the motor 23. This motor has its shaft parallel to the panels. The flywheel 24 therefore rotates in a plane perpendicular to the panel. The same is true of the crank disk 26.

The bars 20, 20 have lugs 35, 35 mounted in front opposite the lugs 31, 31. These lugs 35, 35 form pivot pins for bell crank levers 36, 37. The outer arms of the levers 36, 37 are pivoted to the lugs 32 and 33 respectively. The inner arms of the levers 36, 37 are slotted to receive a crank pin 38 on the crank disk 26.

This modification is of value where the movable panels are light and can be guided in vertical direction without special means for preventing their lateral dislocation.

Figs. 9 and 10 illustrate a further modification in which the slide 12 is reciprocated by the connecting rod 29 from an oscillating motor. As shown, the lower bar 20 carries an oscillating pneumatic motor 39. This has a

crank 40 which is pivotally connected to the connecting rod 29. As the crank 40 oscillates from side to side, the slide 12 is also caused to reciprocate. This gives the same change to the position of the panels as above described.

By the use of the several means described above in detail, the invention is advantageously used to display signs, slogans, designs and even human figures in an animated fashion indicative of growth, extension or enlargement. Thus it may be used as advertisement to attract the eye of the observer and give an impression of desired change or result.

The moving panel or panels may be ornamented or decorated to cooperate with the fixed sign and dominate the latter.

The device is cheap to manufacture, simple to assemble, and rugged in use.

While the preferred form of the invention has been illustrated and described by way of example, it is not intended as a limitation to the scope of the invention other than as defined by the following claims.

What I claim is:

1. An extendable sign exhibitor comprising a housing having a front opening, a fixed panel mounted in parallel spaced relation behind the front opening, a vertically movable panel in front of the fixed panel, a horizontal laterally extending track carried by the fixed panel, a slide in the track, a pair of parallel links pivotally connecting the movable panel and the slide, a rotary motor mounted on the housing, a crank on the motor and a connecting rod from the crank to the slide.

2. An extendable sign exhibitor comprising a housing having a front opening, a fixed panel mounted in parallel spaced relation behind the front opening, a pair of vertically movable panels in front of the fixed panel, a horizontal laterally extending track carried by the fixed panel, a slide in the track, a pair of parallel links pivotally connecting each panel and the slide, a rotary motor mounted on the housing, a crank on the motor and a connecting rod from the crank to the slide.

3. An extendable sign exhibitor comprising a housing having a front opening, a fixed panel mounted in parallel spaced relation behind the front opening, a pair of vertically movable panels in front of the fixed panel, a horizontal laterally extending track carried by the fixed panel, a slide in the track, two spaced pivots on the slide, a pair of parallel links pivoted to each movable panel, one link of each pair being attached to each of the slide pivots, a rotary motor mounted on the housing, a crank on the motor and a connecting rod from the crank to the slide.

4. An extendable sign exhibitor comprising a housing having a front opening, a fixed panel mounted in parallel spaced relation behind the front opening, a vertically movable panel in front of the fixed panel, a rotary motor mounted on the housing, a fly wheel on the rotary shaft of the motor, a crank disk removably attached to the fly wheel and linkage connecting the crank disk with the movable panel.
